FRANK EARNEST CARLBERG, OF PLEASANTVILLE, PENNSYLVANIA.

PUMPING APPARATUS.

Application filed February 17, 1928. Serial No. 255,115.

This invention relates to a pumping apparatus and in its broader aspect contemplates the provision of pumping apparatus suitable for pumping liquids in any form.

5 The invention in its more specific aspect, however, relates to that type of pumping apparatus more usually employed in oil wells, and belongs to the type of pumping apparatus in which a working barrel provided with a 10 reciprocating pumping plunger is provided.

Heretofore in pumping apparatus of this general character the pumping has been effected by the employment of check valves in combination with cup washers which are reciprocated within the working barrel or casing and carry the entire weight of the column 15 of liquid. These cup washers soon become worn and require frequent replacement. In accordance with my invention, the use of 20 cup washers for pumping is obviated.

In my improved pumping apparatus I provide a compressible packing member which is carried by the reciprocating pump plunger and moves within the working barrel.

25 It is a specific object of the invention to provide a structure for permitting the adjustment of the packing member at any position in the stroke of the reciprocating plunger.

It is furthermore an object of the invention 30 to seal the working barrel against the admission of liquid from the well casing above the working barrel and thus relieve the load carried by the reciprocating pumping element.

35 The invention has for its broader object the provision of an improved pumping apparatus which can be economically constructed and which may be operated with efficiency for prolonged periods without necessitating 40 the removal of the working barrel and associated elements.

In the drawings forming part of this specification,

Figure 1 is a side elevational view with 45 parts shown in section of my improved pumping apparatus, showing the same in position within a well;

Fig. 2 is a detailed sectional view of the upper end of the upper working barrel;

50 Fig. 3 is a detailed sectional view of the lower end of the lower working barrel, showing the associated check valve;

Fig. 4 is a detailed sectional view of the reciprocating hollow plunger with its associated check valves and pump packing;

Fig. 5 is a detailed sectional view of the lower end of the upper working barrel, showing the manner in which the same seats on the lower working barrel, and

Fig. 6 is a detailed cross sectional view 60 taken on the line 6—6 of Figure 5.

The well casing 1 is adapted to receive and have lowered therein, the upper working barrel 2. The casing 1 carries at its lower end the lower working barrel 3, which is secured to the casing through the medium of a screw-threaded collar 4. Positioned below the lower working barrel 3 and carried thereby, is a perforated pipe section 5, from which the liquid is admitted to the working barrel 6, shown in detail in Figure 3. This check valve 6 permits the fluid from the well to enter the lower working barrel while preventing its return back into the well. The 70 check valve 6 is held in position within the working barrel 3 by a plurality of friction cup washers 7 and is also provided with a suitable cage 8 for limiting the movement of the ball valve member. The cage 8, it will 75 be noted, carries a threaded neck 9 for receiving a pull rod to permit the valve 6 to be removed from the well in the event its removal should be made necessary for any cause.

The upper working barrel 2, as stated, is adapted to be lowered into the well after the casing 1, the lower barrel 3, and the valve 6 are in place. The upper working barrel carries at its lower end an annular closure 90 member 10, see Fig. 5, which threadedly engages the inner surface of the lower end of the upper working barrel 2, as shown at 11. This closure member 10 seats on the upper end of the lower working barrel 3, as shown 95 at 12 and supports the upper working barrel 2. This closure member 10 is interiorly threaded at 13, and has threaded therein the downwardly projecting tube 14 which is adapted to receive the annular washer or 100 collar 15 on its lower end. Intermediate the closure member 10 and the collar 15 the tube 14 carries alternately disposed friction cup washers 16 and spacing metallic collars 17.

It will be noted that the tube 14 projects a 105 considerable distance into the lower working barrel 3 and that the friction cup washers 16 bear against the inner wall thereof to normally hold the upper working barrel 2 and the lower working barrel 3 in fixed rela- 110

tion. The arrangement is such that the upper working barrel 2 can be removed from the well should such action be necessitated.

The upper end of the upper working barrel 2 is interiorly threaded to receive the annular closure member 18, note Figure 2. The upper end of the barrel 2 is also cut away to provide the shoulder 19 upon which rests the washer or collar 20. A similar washer or collar 21 is provided immediately below the closure member 18 while compressible packing material 22 is positioned between the collars 20 and 21. The arrangement is such that rotation of the closure member 18 will release or compress the packing between the collars 20 and 21, depending upon the direction of rotation of the closure member 18. It will thus be seen that a very effective packing member is provided at the upper end of the upper working barrel.

Thus far only the parts of the pumping apparatus which normally remain relatively fixed, have been described. I will now describe the movable elements of the apparatus.

The reciprocating pump rod 23 extends down into the well casing 1 from the surface where its upper end is held against rotation but free for reciprocation by conventional mechanism. The rod 23 connects with the valve cage 24 secured to the upper hollow section 25 of the pump plunger. The plunger section 25 removably carries at its upper end the ball valve seat 26 (Fig. 2), on which the ball check valve 27 is adapted to seat. The upper plunger section 25 reciprocates within the stuffing box joint formed by the closure 18, washers 20 and 21, and the packing 22, which joint effectively seals the upper end of the working barrel 2. It will be observed that the closure member 18 supports the load or weight of the column of liquid within the casing 1.

The lower end of the plunger section 25 is threaded and receives the upper part 28 of a check valve casing indicated generally at A (Fig. 4). The lower part 29 of this check valve casing is threadedly secured to the upper part 28, as shown at 30. The lower part 29 carries the removable ball valve seat 31, on which is seated the ball valve 32, limited in its vertical movement by the cross pin 33. The lower part 29 of this valve casing A has openings 34 to permit the passage of liquid from the working barrel 2 into the interior of the reciprocating plunger. The part 29 is interiorly threaded and receives the upper end of the intermediate hollow plunger section 35 which is provided with oppositely threaded ends 36 and 37 for a purpose to be hereinafter described.

The plunger section 35 threadedly carries at its lower end the upper part 38 of a check valve casing indicated generally at B. Due to the oppositely threaded ends 36 and 37 of the section 35, it will be appreciated that rela-

tive rotation between the lower part 29 of valve casing A and the upper part 38 of valve casing B will cause the parts 29 and 38 to both move toward each other or recede from each other, depending upon the direction of rotation.

The lower part 39 of valve casing B threadedly engages the upper part 38 at 40 and carries the removable valve seat 41 in which the ball valve 42 seats. The cross rod 43 acts to limit the vertical movement of the ball valve 42. The lower part 39 of the valve casing B has openings 44 for admission of fluid to the plunger. The lower section 45 of the hollow pump plunger is carried by the lower part 39 of the valve casing B. This lower section 45 is perforated as shown at 46, and has the longitudinally extending groove 47 for receiving pins 48 which project inwardly from the fixed tube or sleeve 14, through which the lower section 45 reciprocates. The groove 47 and the pins 48 are arranged to permit free reciprocation of the pump plunger for a full stroke while preventing rotation of the lower hollow section 45 of the plunger.

The intermediate hollow plunger section 35 carries the spaced apart washers or collar members 49, intermediate which are disposed the packing rings 50 of any suitable compressible packing material. Since the lower plunger section 45 is held against rotation by the cooperative relationship of groove 47 and the pins 48, it will be seen that by rotating the pump rod 23 a relative rotation of the valve casings A and B will be effected, causing a compression or a release of compression on the pump packing 50 carried by the intermediate plunger section 35, this action being due to the oppositely threaded ends 36 and 37 of the intermediate section 35.

It will, of course, be understood that suitable locking means may be provided to prevent relative rotation of the upper and lower parts of the respective check valve casings A and B and that locking devices may also be provided to prevent rotation of the valve casing A with respect to the upper plunger section 25 and to prevent rotation of the valve casing B with respect to the lower section 45.

It will also be noted that a rotary movement of the lower plunger section 45 is prevented at all vertical positions of the plunger in making a complete stroke and that, therefore, the packing rings may be expanded at any point in the stroke of the pump. This is important since it permits the packing rings to be expanded out to the wall of the working barrel at the points where the wall is worn, and thus insures a tight fit of the packing throughout the entire pump stroke.

It will further be apparent that since the rod 23 is normally held against rotation at the surface of the well and the lower plunger section 45 is restrained from rotation at the

bottom of the well, no undesirable relative rotation of the pumping rod sections will occur.

In operation the liquid from the well enters the lower working barrel through the check valve 6, and thence enters the lower section 45 of the reciprocating pump plunger, whence it rises through the check valve casing B and is forced by reciprocation of the plunger and the packing 50 to rise through the check valve casing A and be delivered through the check valve 27 to the well casing above the working barrel, where the weight of the liquid is carried by the closure member 18 and prevented from acting against the reciprocating packing 50.

From the foregoing it will be appreciated that I have provided a novel pumping apparatus which is so constructed as to permit repeated adjustments of the pump packing and to enable the adjustment of the packing at any point in the pump stroke. This apparatus will, therefore, function efficiently over long periods of time without necessitating the removal of the working barrel and the replacement of the worn parts.

Having thus described my invention, what I claim is:—

1. In a pumping apparatus, the combination of a working barrel, a reciprocable hollow plunger mounted in said working barrel, a packing carried by said plunger for engagement with said working barrel, said hollow plunger including means for expanding said packing, and holding means cooperating with said plunger throughout the entire stroke thereof, whereby expansion of the packing at any point in the stroke of said plunger may be effected.

2. In a pumping apparatus, the combination of a working barrel, a hollow plunger reciprocable within said working barrel, said hollow plunger including an upper section, a lower section, and an intermediate section, said sections being arranged for relative rotation, a packing member carried by said intermediate section adapted to be expanded by relative rotation of said sections, and means for holding the lower section against rotation during the entire stroke of said plunger to permit said upper and intermediate sections to be rotated relative thereto.

3. In a pumping apparatus, the combina-

tion of a reciprocable sectional hollow plunger mechanism, a working barrel within which said hollow plunger mechanism reciprocates, and means carried by said working barrel cooperating with one section of said plunger for preventing rotation of said section of said reciprocable hollow plunger mechanism in all vertical positions of the plunger during a normal stroke thereof.

4. In a pumping apparatus, the combination of a working barrel, a sectional hollow plunger reciprocably mounted in said working barrel, certain sections of said hollow plunger being constructed to rotate relative to other sections thereof, and means carried by said working barrel for holding one of said sections against rotation at all vertical positions of said sections.

5. In a pumping apparatus, the combination of a lower working barrel, an upper working barrel, a closure member carried by the lower end of the upper working barrel constructed to seat on the upper end of the lower working barrel, a reciprocable sectional pump plunger mounted in said working barrel, and means carried by said closure member for preventing rotation of the lower section of said pump plunger.

6. In a pumping apparatus, the combination of a working barrel, a pair of reciprocable check valve casings mounted in said working barrel, means connecting said valve casings constructed to permit relative rotation thereof, a compressible packing disposed between said valve casings, and means carried by said working barrel for preventing rotation of one of said valve casings.

7. In a pumping apparatus, the combination of a well casing, a lower working barrel, an upper working barrel seated on the lower working barrel, a reciprocable plunger mounted in the upper working barrel for receiving liquid from the lower working barrel and delivering the liquid to the casing above the upper working barrel, a packing member fitted in the upper end of the upper working barrel for preventing return of liquid from the casing into the upper working barrel, said reciprocable plunger being of sectional formation and certain of the sections thereof constructed for relative rotary movement within the upper working barrel.

FRANK EARNEST CARLBERG.
